UNITED STATES PATENT OFFICE.

WALTER CORBETT AND WILLIAM BURNS, OF ST. LOUIS, MISSOURI.

IMPROVED LOCK.

Specification forming part of Letters Patent No. 55,244, dated June 5, 1866.

To all whom it may concern:

Be it known that we, WALTER CORBETT and WILLIAM BURNS, of the city and county of St. Louis, and State of Missouri, have invented a new and useful Improvement in Locks; and we hereby declare that the following is a full, clear, and exact description thereof, reference being had to the accompanying drawings and to the letters of reference marked thereon.

Figure 1 of the accompanying drawings is a sectional elevation of one of the improved locks. Fig. 2 is a transverse sectional elevation through the axis of the key. Fig. 3 is an elevation of the bolt. Figs. 4, 5, 6, 7, 8, and 9 are elevations of different tumblers that are or may be used in the construction of this lock.

This invention relates—

First, to the construction and arrangement of the bridge, wards, guards, and key-hole bushes in such a manner as to render it difficult or impossible to operate upon the tumblers with any burglarious instrument.

Secondly, to the improved construction of the tumblers by notching in an irregular manner the edges of the slot in each of them through which the stud or post erected upon the bolt is made to pass. The said stud or post is also constructed in a peculiar manner, by making each of its sides and its rear edge concave, thus forming an acute angle at each of its rear angles, which said acute angles will more readily enter the aforesaid notches in the tumblers than would an obtuse or a right angle. This construction will render it extremely difficult for any burglarious instrument to raise the tumblers so as to allow the bolt to slide back, for the stud or post will be continually catching against some of the notches of the tumblers, and not until they are each and every one relieved can the bolt be withdrawn. The number of tumblers in a lock may be increased indefinitely, and increased security afforded in the same ratio. The construction of the tumblers is also improved by two notches in their bottom edges, one on each side of the key-bed, thus increasing the distance which any instrument would have to go to reach the tumblers to operate upon them burglariously.

Thirdly, this invention relates to the construction of the bolt with two notches in its bottom edge, so that if it should be thrown partly back by any instrument, so that the key cannot enter its proper notch to operate it, the key may

be turned up against the second notch and the bolt thereby thrown forward, when the key can be turned around the other way and the bolt then thrown back, as usual.

Fourthly, a stop or catch, such as is used on night-latches, will be employed on this lock, to afford increased security during the night-time; and

Fifthly, the end of the key will be cut off even with the end of the key-hole bushes, so as to prevent the possibility of taking hold of the key with "nippers" or "outsiders" should the key be left in the lock.

To enable those skilled in the art to make and use our lock, we will proceed to describe its construction and operation.

A represents the ordinary shell or case of the lock. This part is constructed in the ordinary manner, and needs no further description.

B is a bridge which is constructed in the central portion of the lock, parallel with the two side plates of the lock and across that portion of it which is traversed by the key. It is connected with the shell or case of the lock by means of two partition-walls, B', which are placed far enough from the center of the key-hole to permit the key to be turned around between them. A ward, a, is placed within the circular opening for the key in the center of the bridge, as shown clearly in Fig. 1. This ward should extend from the vertical slot of the key-hole, as shown, below the axis of the key, up over the annular opening, and down on the other side of A, to a point nearly or quite opposite the place where it started, thus inclosing about seven-eighths, more or less, of the said annular opening within its circumscribed area. This ward is made just as wide as it can be and allow sufficient room between it and the side walls of the lock to afford the requisite strength to the key where it passes this point.

There are key-hole bushes a', of a shape similar to the ward a, and clearly shown in Figs. 1 and 2. These bushes are of the size necessary to fit the shank of the key used, and are fitted and fastened into the side plates of the case A, as clearly shown, their inner ends extending inside of and overlapping the outer edges of the ward a, so that it will be extremely difficult for any burglarious instrument put into the key-hole to pass up above the ward a, as the bushes a' will convey such instrument so used inside of the outer edges of the ward a, which

will then afford a considerable resistance to the farther progress of the instrument. In case any instrument should pass outside of the ward a , there are guards a^2 attached to the bridge-walls B' , which would stand ready to intercept the progress of the implement before it reached the tumblers of the lock, which are located immediately over the ward a .

The general form of the tumblers C is not materially different from that in common use, but the details of their construction are such as to render it extremely difficult to move the bolt forward or backward without the use of a proper key. These tumblers may be made in many different forms in the same lock, some of which variations are shown in Figs. 4, 5, 6, 7, 8, and 9. In all of these, however, there are these general features: There is a mortise, b , near one end, which is placed upon the post b' when they are in place in the lock. There is also in the opposite end a slot, b^2 , which is formed more or less irregularly. The post or stud b^3 , erected upon the bolt D , passes up through the slot b^2 when the tumblers are in place in the lock. The post b^3 is formed with its sides and rear edge concave, so that its two rear corners will be acute angles. There is in the top of each of the tumblers a spring, C' , for the purpose of holding the tumblers down to their bearing on the post b^3 .

The improvements in the tumblers consist in notching the edges of the slot b^2 with the teeth c . These notches may be made at regular intervals; but we prefer to make them irregularly. Their office is to catch on the acute corners of the post or stud b^3 in case they are thrown up by any burglarious instrument and the bolt partly thrown back. A further improvement consists in cutting a notch, c' , in the bottom edge of the tumbler, each side of the bearing c^2 for the key.

The bolt D has two notches, E and E' , cut in its bottom edge. The notch E is the one which the key will habitually enter to move the bolt backward or forward. In case, however, the bolt should have been partly thrown back by any outside attempt to open it, the key F will be found to strike the bolts in the position of the dotted lines F' , and will in that

position be unable to move the bolt either way or to enter the notch E at all. To overcome this difficulty a second notch, E' , is cut in the bolt, farther back than E , and into this notch the key may be turned and the bolt thrown forward to the position shown in Fig. 1, when the key can be turned back, and it will then enter the notch E and work the lock as usual.

A stop or catch, G , worked by a knob on the outside of the lock (not shown) is fitted to enter a notch, g , in the bolt. This catch G is similar to one used in night locks or latches, and may be used in connection with this lock for the same purpose.

The end of the key is cut off straight, even with the outside of the key-hole bush, so that no burglarious instrument can be fastened to it to open the lock should the key be inadvertently left in its place during the night-time or absence of the inmates.

It should have been mentioned that there is a ward, a^o , fastened to the outer walls of the shell of the lock on either side, as shown in the drawings, and for the same purpose for which the ward a and key-hole bushes a' are used.

Having described our invention, what we claim is—

1. The combination and arrangement of the bridge B and wards a a^o and key-hole bushes a' , as above recited.
2. The tumblers C , when constructed with the toothed notches c and the notches c' , and also in connection with the post b^3 .
3. The combination of the stop G with the above-described lock, as and for the purpose set forth.
4. The construction of the bolt D with two notches E and E' , as and for the purpose set forth.

5. The combination and arrangement of the various parts of this lock, viz., the bridge B , the wards a and a^o and key-hole bushes a' , the tumblers C , the post b^3 , and the stop or catch G .

WALTER CORBETT.
WILLIAM BURNS.
